HIGH CAPACITY WEAVING MACHINE

Rudolf Rossmann, Gauting, near Munich, Germany, assignor to Tefag Textil-Finanz A.-G., Zurich, Switzerland

Application July 19, 1934, Serial No. 736,117
In Hungary July 20, 1933

32 Claims. (Cl. 139—125)

This invention relates to a loom of high efficiency which constitutes an improvement, compared with existing types, with respect to the number of picks per minute and the possibility 5 of using it for various kinds and sizes of fabrics.

The development of the power loom with a view to increasing its output has hitherto been frustrated by the fundamental principle of construction involved. Mass forces, which are known to 10 increase considerably with increase in speed, become so great that safe functioning of the individual members of the loom is not ensured any longer. Furthermore, strain on the yarn increases to such an extent that thread breakages 15 take place quite frequently.

An object of this invention is to provide a gripping shuttle loom which is free from defects of existing looms employing gripping shuttles and selectors and which is capable of increased output, produces a perfect fabric and affords maximum protection to the yarn. According to the 20 invention, the weft thread is inserted in the shed always in the same direction and in a path independent from the movement of the slay by 25 circulating gripping shuttles and is held on both sides until beaten up against the edge of the cloth, while the empty gripping shuttles are returned to picking position outside the shed. It is, therefore, possible to employ a larger number of 30 shuttles of the same type during the operation, and, for this purpose, the weft thread can be caught at both ends by special means disposed on the fabric edge after the shuttle has traversed the shed. These holding means preferentially move forward together with the reed when the weft is beaten up and release the weft thread ends only after the blow of the slay when the weft thread has been secured. In this way, regular and rapid insertion and uniform beating 35 up of the weft thread are ensured. The gripping shuttle used is preferably fitted with a thread gripper or clamp which can be controlled from without by a member getting into engagement therewith, preferably on one long side of 40 the shuttle.

The jacket of the gripping shuttle consists preferably of a projectile-like steel body pointed at one end and having a gripper at the rear end. 45 It is an object of this invention to provide a power loom having gripping shuttles and in which the path for the shuttles is independent from the motion of the slay and in which the shuttles are thrown through the shed formed while 50 the slay stands still in the rear dead center. For

this purpose, control of the slay motion is effected by a curve causing the slay to dwell for some time in the rear dead center. In the known constructions of this kind, the shuttle is picked while the slay is moving so that the shuttle, by its own inertia and the motive forces of the slay, is pressed against the reed and guided thereon. When the shuttle is picked while the slay stands still, the relative speed of the shuttle and thus the working speed can be increased. 10

A further object of this invention resides in the provision of a power loom in which the boxes between which the shuttle moves are arranged stationarily on the loom. Hitherto they were disposed on the slay and cooperated in the reciprocating movement thereof. The stationary arrangement of the shuttle boxes affords the advantage that the slay can be made much lighter and thus permit of a much more rapid motion, since it carries only the reed and not the shuttle boxes with all the shuttle driving and braking members and a larger or smaller number of shuttles. By combining a long stop of the slay in the dead center opposite the stationary shuttle boxes with a small and, therefore, rapidly moving gripping shuttle, a high efficiency loom is produced with which the usual output is exceeded by far. A particularly rapid motion of the shuttles can be attained by accelerating them by means of a crank mechanism kept continually in motion and carrying out a working stroke after a few idle motions. 15 20 25 30

Another object of the present invention resides in the provision of a power loom having, in addition to means insuring great acceleration of the shuttle, braking means which brake the shuttle gradually or apply a stepwise increasing braking force, for example, by a number of braking elements operating independently from one another. 35 40

It is a further object of this invention to provide a power loom in which the shuttle box serving for catching and braking the gripping shuttle is arranged displaceably in the direction of the pick, so that it can be pushed close up to 45 the fabric edge whatever the width of the cloth may be. In this way, unnecessarily long, free weft thread ends are avoided, and the loom can be better adapted to changed operating conditions. 50

Another object of this invention is the provision of a power loom having an especial thread giving member for taking over the weft thread from the stationary bobbin to the shuttles, said member delivering the thread very quickly, al- 55

most instantly, yet reliably to the gripping shuttle which, for this purpose, is fitted on one side with a thread gripper while the thread giver also has a gripper disposed in staggered relation to the shuttle gripper. The gripper of the thread giver delivers the weft thread to the gripping shuttle prior to each picking and releases the weft thread during the winding off.

Another object of this invention resides in the provision of a power loom in which the free ends of the inserted weft thread held by special holding means are inserted, after beating up and after the formation of the new shed, into the latter either by the holding means themselves or by special means such as grippers or hooked needles. Thus, a uniform and very firm edge is produced since the weft threads are doubled therein. The character of the fabric can, therefore, be determined as desired by holding the weft thread ends until the blow of the slay takes place, while the edge is formed afterward.

In view of the high picking speed, it is advisable to effect the motion of the shafts also by novel means. Hitherto, the shafts were constructed in the form of extended beams or carriers extending over the whole length of the loom which, of course, involved a relatively great weight.

It is an object of the present invention to provide a power loom having a shaft drive the shafts of which are supported and moved from below by a plurality of members arranged in a row, while their control preferably takes place from the side of the machine. The free carrying length of the individual shafts is thus considerably reduced so that the shafts themselves can be made much lighter, while the larger number of driving members insures reliable and precise shaft motion.

Another object of the present invention resides in the provision of a power loom in which thread breakages and, especially, breakages of the warp threads are reduced to a minimum. The warp threads are known to be considerably effected by each beating up, owing to the friction of the heald eyes, and will often break at weak points. This danger can be reduced by causing the warp threads to move slightly to and fro within the eyes during beating up. Examinations of the edge of woven fabric have shown that the to-and-fro motion of the warp threads is due solely to their elasticity.

An object of this invention is to provide a power loom in which the to-and-fro motion of the warp threads and the danger of thread breakage connected therewith is reduced by decreasing the free stretching length of the warp thread and of the fabric exposed to the mechanical action of the slay. For this purpose, two special carrier rollers are provided, one of which is located above the warp beam and constructed as a thread braking roller, whereas the other replaces the breast beam and serves as a take-up roller. The speed of these rollers is such that the natural shrinkage due to the insertion of the weft threads is compensated and the adjusted or desired tension of the warp obtained. The free length of the warp can thus be reduced to a fraction of what it used to be and, thereby, also the elastic swinging and rubbing of the warp threads on the heald eyes.

In existing looms, fabrics are often damaged after the weaving process by so-called temples or spreaders fitted with non-independently moving wheels, the frictional resistance of which causes the damage to the fabrics. At high loom speed, the damage can be very troublesome.

It is an object of the present invention to provide a power loom having a spreader system capable of withstanding high speeds, comprising special grippers located on the edges of the fabrics and provided with clamping jaws that can move vertically to the path of the web above and below the latter, the jaws being fitted with holding means such as teeth, pawls and the like for drawing the fabric outward in both directions without interfering with the taking-up.

A further object of this invention is to provide a new loom in which the various parts, in so far as they have to do with weft insertion and fabric formation, are suitably arranged on a single central carrier extending transversely through the machine. This central carrier insures precise and thorough fastening of these parts which formerly used to be disposed, as a rule, somewhat loosely between the two loom frames and, in addition, affords a considerable economic advantage in assembling the loom as all parts required for weft insertion and fabric formation can be firmly mounted on the central carrier in the shop and need not be put on on the spot, which involves a large saving.

Further and other objects of the present invention will be hereinafter set forth in the accompanying specification and shown in the drawings which, by way of illustration, show what I now consider to be a preferred embodiment of my invention.

In the drawings:

Fig. 1 is a front view of the machine with the left-hand side thereof, whence the picking takes place, partly shown in section or opened.

Fig. 2 is a view of the machine from the front and right, i. e., from the catching side, and showing the driving members.

Fig. 3 shows, by means of an isometric diagrammatic drawing, more particularly the slay drive, the circulation of the shuttle, the means for changing the position of the shuttle box, the mechanisms associated with the shuttle boxes and a modified construction of the reed.

Fig. 4 is an isometric diagrammatic showing of a loom according to my invention with several parts broken away and particularly illustrating the operation of the shafting and the operating mechanism of the heald frames.

Fig. 5 is an isometric diagrammatic showing of the shuttle and the thread giving member according to my invention in the position just before the weft thread is taken over by the shuttle.

Fig. 6 is an isometric diagrammatic showing of the shuttle and the thread giving member according to my invention in the position in which the weft thread is taken over by the shuttle.

Fig. 7 is an isometric diagrammatic showing of the shuttle and the thread giving member according to my invention in the position after the weft thread has been taken over by the shuttle, the shuttle being already on its way across the loom.

Fig. 8 is a diagrammatic isometric showing of the mechanism for picking the shuttle.

Fig. 9 is an isometric diagrammatic showing of the mechanism for operating the shuttle and the thread holder in combination with a loom having the type of reed shown in Fig. 3.

Fig. 10 is a diagrammatic plan view of one form of a braking device for the shuttle.

Figs. 11, 12, and 13 show how the thread ends are bent into the shed to produce an edge, Fig. 11 illustrating the beating-up position, Fig. 12 the hooked needle engaging the weft thread end

from below, and Fig. 13 the drawn-in thread end.

Fig. 14 is an isometric diagrammatic showing of the hooked needle illustrated in Figs. 11-13 and a fabric spreader and the mechanisms for operating both devices in combination with a loom having the type of reed illustrated in Fig. 3.

Fig. 15 shows an arrangement of the carrier rollers for warp and fabric.

10 In all figures, like parts are designated by like numerals.

Referring more particularly to the drawings:

Figs. 1 and 2 show a loom in which the two side frames 1 and 2 are connected by the central carrier 3 on which the bearings 4 are supported. 5 is the main driving shaft, 6 denotes the slay arms or swords, 7 the slay, and 8 the reed secured thereto which, in Figs. 1 and 2, is shown as having a hooked configuration in order to 15 constitute a guide for the shuttle. Behind the bearings 4, the driving mechanisms 9 for the shafts 10 are secured to the carrier 3, and, on the left side, the casing 11 for the picking means for throwing the shuttle, while to the right there 20 is the casing 12 for the catching means for catching and braking the shuttle. The casings 11 and 12 contain also the members required for control. The upper side of the casings 11 and 12 is preferably flat and provided with an upstanding rim so as to form a tray on which the operator may place tools etc. 13 is the driving motor for the shuttle drive and 14 the casing of the dobby. 15 is the casing for a central lubricating apparatus.

35 On the right-hand side, there is the casing 15 for the feed mechanism comprising the feeding members for the two carrier rollers, for the warp 16 and the fabric 17. The carrier roller 18 for the fabric 17 is here shown in the form of a tube and partly visible in section. The carrier roller 19 for the warp is supported by a shaft 19' on the rear side of the loom. 20 is the beam on which the fabric is wound up.

40 In Fig. 2, there are further visible to the right the driving members, namely, the clutch 21 on the main shaft 5, the driving motor 22 and the speed changing gear 23, while to the left the edge forming apparatus 24 can be seen.

45 The warp threads are rolled up on the warp beam 25 and pass therefrom over the warp carrying roller 19. The production of the fabric takes place by causing the weft thread coming from one or more bobbins not shown to be thrown by gripping shuttles transversely to the warp threads from the picking means in casing 11 through the tunnel-shaped reed 8 into the catching member within casing 12, whence the shuttles are returned to the casing 11 and caused to take up the weft thread. The finished fabric rolls over roller 18 and is finally wound up on the beam 20.

50 In Figs. 2 and 4, the mechanism for starting up and stopping the loom is illustrated. When starting the loom, the motor 22 is first started. 55 By means of belt 74, this motor drives the variable gear 23 and therefrom, by means of belt 74', the driving member of the clutch 21 which serves, at the same time, as a fly wheel. In order to move the driven member 75 onto the driving member and to produce engagement of the clutch, the starting and stopping rod 60 extending across the whole width of the loom and being easily accessible for the operator must 60 first be pushed to the left. Rod 60 takes bell

crank 61 with it to which it is rotatably connected by bolt 76. The end of one arm of bell crank 61 is provided with a roller 77 which abuts against the flap 78 projecting from the side frame 2. To the end of the other arm 84 of bell crank 61, connecting rod 68 carrying operating rod 68' is linked which is pulled upward against the tension of spring 79 (see Fig. 4) whenever the bolt 76 is carried to the left within the slot 76' upon movement of rod 60 to the left. 10 As can be seen in Fig. 4 rod 68' carries a tooth 80 cooperating with a finger 81 which is swingably mounted within the box 64. Tooth 80 in cooperation with finger 81 locks the rod 68' in its upper position. To rod 68 brake lever 66 is 15 connected by means of link 65. In the upper position of rod 68, lever 66 loosens the brake band 82 and releases it from the brake disc 83 which is associated with the driven part of clutch 21. The upper side of arm 84 of bell crank 20 61 has a notch 85 which cooperates with finger 86 of the lever 62. This lever operates the shaft 87 which, upon a clockwise movement of lever 62, pushes, by means of cam 203, the driven part 25 75 of the clutch 21 on to the driving part of the clutch and engages the clutch. In order to engage the clutch, the rod 60 must first be pushed to the left until finger 81 engages tooth 80; arm 84 thereby moves sufficiently far upward 30 to permit engagement of the notch 85 and finger 86 upon a movement of rod 60 to the right. The latter movement must be carried out against the tension of spring 89. Main shaft 5 is connected to driven part 75 of the clutch 21, and the loom 35 operates as long as rod 60 is maintained in the position furthest to the right. This position may be maintained by a coupling not shown which may be engaged by a slight turn of the starting rod 60.

40 Should there be any irregularity in the operation of the loom, for example, a broken weft or warp thread, this may be detected by a feeler not shown in the drawings, because it is described in my corresponding application Ser. No. 672,389 which matured into Patent No. 2,051,902. This feeler operates an electric switch closing an electric circuit of which the solenoid coil 88 is a part. Finger 81 is linked to the core of this solenoid coil and is turned counter-clockwise when this coil is energized. Finger 81 is thereby pulled out of engagement with tooth 80, and rods 68' and 68 are pulled downward by the action of spring 79. With rod 68, the arm 84 is also pulled downward, and notch 85 snaps out of engagement with finger 86 which, under the influence of spring 89, moves counter-clockwise taking shaft 87 with it and disengaging the driven part 75 from the driving part of coupling 21 so that no power can be transmitted to the loom. In order to stop the loom immediately, brake 82-83 is provided, the brake band 82 being applied by the downward movement of rods 68' and 68 whereby lever 66 pulls brake band 82 onto brake drum 83. It is obvious that, for the operation described, the power of spring 79 must be greater than that of spring 89, and it is further obvious that the machine cannot be started again as long as the solenoid is energized, i. e. as long as nothing is done to put an end to the irregularity. 55 As long as solenoid 88 is energized, movement of the starting rod 60 to the left is possible, but, upon movement to the right, bellcrank 84 will always go all the way down again and have no chance to engage the finger 86 of lever 62. 60 65 70 75

Fig. 3 shows a mechanism more particularly described in my copending application Ser. No. 673,227 which matured into Patent No. 2,039,454 which causes the slay to stay in the rear dead center during the entire motion of the shuttle and also shows how the circulation of the shuttle takes place. Parts of the loom are broken away to make the vital parts of the mechanisms shown in Fig. 3 more clearly visible. The slay 1 is secured to the bent two-arm levers or swords 6 of which there are several; they are turned about the shafts 26 by means of the cams 27 secured to the main shaft 5 and rotating in uniform manner. The reed 8 is mounted on the slay 1 and forms the rear path for the shuttle 90. In Fig. 3, the reed is arranged in a plane; as indicated in Figs. 1 and 2, it can be constructed so as to afford a closed race for the shuttle. The shuttles 90 circulate from the picking side at the left to the catching side at the right and are returned below the fabric by means of a conveying device comprising a band conveyor 28 moving on two rolls 29, the one on the left side being visible on Fig. 3. From the conveyor band 28, the shuttles 90 pass first to the plunger 30 in the chamber 31 of the casing 11 and are then guided upward into the picking position in the direction of the arrow, whence they are thrown into the shed and caught by the catching mechanism at the right end of the loom, whence they are brought by means not shown on to the conveyor band 28 and returned to the picking position. A large number of shuttles are always circulating. The catching mechanism is riding on rails 32 on the loom frame in order to be brought close to the edge of the fabric. This feature is one of the subjects of my copending application Ser. No. 673,226 which matured into Pat. No. 2,030,270.

Fig. 4 more particularly shows the shafting and the operating mechanism of the heald frames. With the latter, my copending application Ser. No. 673,224 which matured into Patent No. 2,069,330 deals in particular. The main shaft 5 operates, by means of the transmission chain 205, an auxiliary shaft 91 and, by means of a gear 173, a transmission shaft 92 on which the conveyor rollers 29 are mounted. The latter shaft rotates, by means of another gear 174, a vertical shaft 93, the purpose of which will be described later. The transverse shaft 92 operates, by means of another chain drive 94, the cam shaft 95. The latter carries a plurality of cams 96 which cooperate with rollers 97 attached to the levers 98 which are fulcrumed to the stationary casing 14 at 99. The free end of the levers 98 engages a notch 100 in the longitudinal bars 101 which are oscillatingly operated upon a swinging movement of the levers 98 brought about by the rotation of the cam shaft 95. One crank of the bell crank levers 102, of which there is a plurality arranged across the loom at equal intervals, engages a notch open at the top of bars 101, while the other arm of the bell cranks carries the actuating rods 103 which carry the rigid longitudinal bearers 104. The latter support the lightly built heald frames 105. These frames and the operating mechanism therefor are more particularly described in my copending application Ser. No. 673,224.

The gripping shuttle 90 is more particularly shown in Figs. 5, 6 and 7. It consists preferably of steel and has in front a projectile-like tip and in the rear a cavity for the thread gripper or clamp 34 which may be constructed in different

ways and consist, e. g., of one or several parts. The shuttle jacket has a transverse opening 35 which can be entered by a wedge-like body 36 for opening the gripper, the wedge-like body being moved by the loom drive in a manner to be described later. The position occupied by the thread gripper after the entrance of the wedge is shown on Fig. 5.

The shuttle itself is more particularly described in my copending application Ser. No. 729,760.

Fig. 6 shows the gripper in closed position, i. e., after taking over the weft thread 37. The two end positions of the gripper are limited by the rivet 38 and by correspondingly shaped parts 39 of the gripper. After the gripper has been urged out of its internal position as indicated in Fig. 5, it will open by inherent spring power and release the thread 37. The control of the gripper 34 being effected by an engagement transverse to the axis of the shuttle has the advantage that the point of the shuttle or the surface thereof may be completely smooth and free of projecting portions which could damage the warp threads passing through the shed.

Fig. 7 shows the transfer of the weft thread 25 from the feeding member to the shuttle prior to picking. The shuttle 90 carries the thread gripper 34 which is disposed coaxially but rotated by 90° with respect to the thread gripper of the thread giver or feed member consisting of a feed body 53 to which the two clamping jaws 52 and 54 are secured. The control of the clamping jaws and the operation of the thread feeding member can be better understood from Fig. 3 if viewed together with Figs. 5-7. The shuttle coming from the right end of the loom with clamp 34 projecting and open and riding on conveyor 28 is taken over by plunger 30. As soon as the shuttle rests on the latter, as shown in Fig. 3, plunger 30 is moved upward by means of the cranked lever 55 which is rotatably supported by the casing 11 by means of pin 106. One arm of lever 55 carries at its end a roller 107 engaging a cam 108 which is keyed to the auxiliary shaft 91. Plunger 30 moves so far upward that the shuttle is pressed against the upper wall of the chamber 31 and thus held in position. Now the thread giver holding the weft thread 37 in its claws 52-54, as shown in Fig. 5, guided by groove 176 is moved on a straight path towards the rear end of the shuttle by means of finger 175 slidably projecting from the arm 109 of bell crank 109-110. This bell crank is rotatably carried by the pin 111 mounted to casing 11 and is oscillated by a groove 112 cooperating with roller 113 attached to the end of arm 110. The groove 112 is part of a disc mounted to the vertical shaft 93. The closed jaws 52 and 54 enter in between the open jaws 34 of the shuttle clamp. Then the thread giver body 53 abuts against the clamp 34, pushes it inside the shuttle 90, whereby the clamp 34 is closed. This is due to the spreading configuration of the resiliently opened jaws of clamp 34 which slidably abut against the inner sides of the cavity within the shuttle and are thereby forced toward each other. The jaws of clamp 34, upon closing, engage the weft thread 37. This is now held by the clamp of the shuttle as well as of the thread giver. Now the jaws 52 and 54 of the thread giver clamp 70 must be opened which is done in the following manner: an opening extends through the thread giver body 53 and accommodates a butterfly lever 114 swinging around a pin 115 which is mounted to the thread giver body. At its upper end, the 75

5 butterfly lever has an extension 118 extending through a slot in the upper jaw member 52. This extension can be engaged by an arm 117 of a bell crank lever 109-110 and is operated from a groove in a disc 119 which is also mounted to the vertical shaft 93. Both levers 109-110 and 117-118 are close together; they are spread apart on Fig. 3 in order to make the showing clearer. Upon movement of lever 117 from the position shown in Fig. 6 to the right to the position shown in Fig. 7, it engages the extension 118 and turns the butterfly lever clockwise, thereby spreading the jaws 52 and 54 apart. The 15 thread 31 is now free from clamps 52 and 54, and so is the shuttle 90 which is ready for the pick.

20 Figs. 8 and 9 show a shuttle driving mechanism which is a modification of the mechanism disclosed in my U. S. Patent No. 1,945,996 consisting of a rapidly rotating crank gear having a crank 40, a connecting rod 41 and a sliding member 42 which moves to and fro between two dead centers on a slide rod 43. The gear is 25 operated by a motor 13. The sliding member 42 carries an engageable and disengageable paw 44 which can be controlled, for example, by the driver 45 in the rear dead center position. The driver 45 is engaged prior to picking by control 30 means shown in Fig. 9.

35 A cam 120 is keyed to the main shaft 5 and engages one end of the double lever 121, the other end of which reciprocatingly moves the control rod 45 up and down. By the spring 122, see Fig. 8, the paw 44 is normally held in the position indicated by dotted lines in Fig. 9. In this position, the paw can not engage the shuttle which lies on the upper surface of plunger 30. However, when the rod 45 is in its uppermost 40 position as shown in Fig. 9, the outer end 123 of the paw abuts against the rod, and the paw is turned clockwise against the power of the coil spring 122 when being pushed to the left by the crank gear. After passing dead center, the 45 crank gear pulls the paw to the right, and the projection 124, see Fig. 8, abuts against the rear surface of the shuttle 90 and pushes it to the right. The cam 108 on Fig. 3 operating the lever for moving the plunger 30 is of such configuration that the plunger moves somewhat downward at the moment paw 44 engages the shuttle, so that the shuttle is not pressed any more against the upper side of chamber 31 and is entirely free to be pushed off the plunger 30.

50 Fig. 8 shows the position of the paw for idling, several idling motions being carried out by the crank gear prior to the picking of a shuttle, and the gear being simultaneously somewhat accelerated thereby. Owing to the accelerating pressure due to the inertia of the shuttle, the shuttle 90 is then firmly pressed against the paw 44 and is accelerated, together with the sliding member 42. Approximately in the middle between the two dead centers, the sliding member has reached 55 its maximum speed and is then retarded up to the dead center on the right. During this time, the shuttle 90 detaches itself from the paw 44 and passes ahead of the sliding member 42 out of the chamber 31 and through the shed. By spring 70 122, the paw 44 is brought into the position of rest shown in Fig. 8, while the sliding member 42 again carries out an idle motion.

75 Fig. 10 shows a type of shuttle brake capable of an increasing brake power. This in itself is subject matter of my copending application Ser. No.

673,810 which matured into Patent No. 2,057,114. The catch member 47 associated with the casing 12, shown in Fig. 1, contains a ledge 48 to which a number of braking laminae 49 are attached. The ledge 48 is connected by the toggles 50 with the catch member 47. By means of the draw bar 51, the toggles can be brought out of the erected position into the collapsed position shown by dotted lines, whereby the brake power can be reduced until the brake is fully released. The incoming shuttle 27 is caught first by the first lamina or spring 49' and pressed by it against the opposite interior wall 46 of the catch member casing 47. It is then exposed to the pressure of the following springs, whereby the brake power is increased each time until the shuttle comes to a stop, at the latest, on reaching the last spring lamina. By acting by degrees as shown, the brake is capable of stopping the shuttle always at the same point and of rendering it insensitive to different speeds of passing in. This new type of shuttle brake exerting an increasing brake power upon the shuttle which increases the further the latter moves into the brake is more particularly shown in my copending application Ser. No. 673,810 which matured into Patent No. 2,057,114. That part of the interior of the catch member 47 which is hit by the point of the shuttle, if the applied braking power is insufficient to stop the shuttle at an earlier moment, is provided 30 with an exchangeable buffer 75 made of felt, rubber or the like. At the moment the shuttle passes the shed and enters the catch member 47, the toggles 50 and the ledge 48 are in the position shown in Fig. 10, and the shuttle is definitely 35 held by the spring laminae 49 forcing it against the interior surface 46 of the catch member 47. Now the wedge 36, shown in Figs. 3 and 5, is pushed into and withdrawn again from opening 35 by means of double lever 125 which is revolvably mounted to casing 12 by means of bolt 126. The lever is operated by a cam 127 which is mounted to the auxiliary shaft 91. As described in connection with Figs. 5 to 7, the clamp 34 is moved out of the shuttle 90 and opened by the 40 insertion of the wedge member 36, and the weft thread 37 is released. Member 36 is provided with projections 200 shown in Fig. 5 which abut against the shuttle, when the wedge is inserted, and push the shuttle downward. At the same time, the 45 draw bar 51 is pulled to the right by means of lever 128 which is also revolvably mounted to casing 12 and operated by a curved groove 129 on the disc 131 mounted to shaft 91. This groove 50 cooperates with roller 130 mounted to one end of the double lever 128. The shuttle is now free to fall down on to the conveyor belt 28 which returns it, with the clamp 34 open, to the left side of the loom and on to the plunger 30.

55 Figs. 11, 12, and 13 show how the end of the thread is brought forward on the edge of the fabric up to beating up and is worked into a woven edge. The end of the weft thread 37 is first caught after picking by the gripper 33 which 60 clamps it loosely. When the reed 8 moves forward for beating up, the gripper 33 does the same and holds the end of the thread. After beating up, the gripper 33 remains at first in front, while the reed 8 returns to its rear dead center position to let the next shuttle pass. As soon as the shed 65 67 has opened again, as indicated in Fig. 12, the hooked needle 132 disposed above the fabric and rotatably secured to a shaft 133 passes through the warp threads 16 and under the end of the weft thread 37 held by the gripper 33. During the 70 75

return motion of the hooked needle 132, the hook 134 engages the end of the thread and draws it out of the gripper 33 into the shed in the direction indicated in Fig. 13. The end of the thread is then firmly beaten up together with the next weft thread to produce a reinforced and durable edge for the fabric. This selvedge forming mechanism itself is more particularly shown in my copending application Ser. No. 672,390 which 10 matured into Pat. No. 2,034,487.

The mechanism for operating the gripper 33 synchronously with the reed 8 is illustrated in Fig. 9. A disc 135 is mounted to and revolved with auxiliary shaft 91. The disc 135 has a curved groove 136 cooperating with roller 137 at one end of cranked lever 138. This lever is revolvably mounted on casing 11 by the pin 139 and carries at its other end the finger 140 of gripper 33. Since shaft 91 is coupled to shaft 5 by a chain 90, the curve 136 can easily be arranged so that grippers 33 swing in the same way as the reed 8 which is operated by shaft 5. A finger 141 is slidably mounted to the lever 138 and has a pin 142 cooperating with a stationary guide member 143 which is fixed to casing 11. On sliding over the guide 143, the pin 142 lifts the pin 141 upward and separates it from finger 140, thereby releasing the weft thread. As soon as the pin 142 leaves the guide, the finger 141 snaps down under the influence of spring 144 and forces the thread on to finger 140, thereby holding the thread.

The knife 168 shown in Fig. 3 operates synchronously with the grippers 33. This knife which might also be substituted by a pair of scissors is 35 for the purpose of cutting the weft thread just at the moment when it is being gripped by the grippers 33. It is attached to a lever 171 pivoted by pivot 169 to one wall of the casing 11 and operated by the cam 170 attached to the shaft 91. 40 Since this cam is operated by the same shaft as is the curve 136 operating the grippers, it is obvious that, by a suitable configuration of cam 170 from which movement is transmitted by roller 172 to lever 171, it can easily be accomplished that 45 the knife 169 cuts the weft thread at the moment the thread is engaged by the grippers.

The mechanism for operating the hooked needle 132 is shown in Fig. 14. The needle is provided with a bell crank-shaped part swinging around 50 the pin 133. A link 145 is revolvably connected at one end to one arm of the bell crank. The other end of link 145 is revolvably connected to lever 146 oscillating around the fulcrum 147 of which there is one mounted on casing 11 and 55 one on casing 12. Lever 146 has a roller 148 cooperating with a groove in disc 149 mounted to and revolving with shaft 91. The operation and swinging motion are obvious from Fig. 14.

Fig. 14 also shows a spreader provided with 60 clamping jaws 150 and 151 movable perpendicularly with respect to the path of the fabric and above and below the latter and fitted with teeth 152. The teeth are of such a shape as to offer no resistance to the movement of the clamping 65 jaws toward and over the fabric, while, upon movement of the jaws from the fabric, i. e., outward from the center of the loom, the teeth bite into the fabric. Upon an outward movement of the spreaders, the fabric is stretched with respect to its width, whereas, upon an inward 70 movement of the spreaders, i. e., movement in the direction toward each other, the jaws glide over the fabric. The lower jaw 151 is mounted to its holder 153 in such a way that a horizontal 75 swinging around a pivot 154 is possible, whereas

an up-and-down movement can not take place. The horizontal swinging is limited by an abutment 155 on the holder 153 cooperating with abutment 156 on the jaw 151. Abutment is assured by a spring 157. This arrangement permits 5 the fabric to move forward to a limited extent when the jaws bite into it, thereby pulling the jaws which then rotate somewhat around the pivot 154. The upper jaw 150 is hinged to the lower jaw 151 by means of hinge 158. Upon an 10 inward movement of the jaw holders, i. e., a movement toward each other, the upper jaw will move slightly upward according to the thickness of the fabric, on which it rests due to its weight, and will be pulled down again upon an outward 15 movement of the jaw holders, due to the configuration of the teeth which then bite into the fabric.

The jaw holders are reciprocatingly operated by a lever 159 pivoted to the jaw holder 153 by pivot 160 and to the casing 11 by pivot 161. It is swung by means of a roller 162 cooperating with a curved groove in disc 163 which is mounted to and rotated by the shaft 91. The latter operating synchronously with the main shaft assures that the movement of the jaws to-and-from 25 the fabric is timed in correspondence with the other parts of the loom. The jaw holders move somewhat toward each other upon each beating operation of the reed 8. At that moment, the fabric has its normal width, and the jaws can 30 be opened. Upon the return of the reed to the rear, the jaw holders move outward, and the jaws automatically close on the fabric, thereby stretching the fabric to its normal width. Stretching jaws of the type described assure a 35 definite width of the fabric and do not harm the material.

Fig. 15 is a side view of the loom particularly showing the drive of the warp and fabric carrying rollers. A variable gear mechanism 164, which 40 is not shown in particular and which may be driven by the main motor 22 or an independent source of power, operates the chains 165 and 166 which drive the warp carrying roller 19 and the cloth carrying roller 18 at desired speed as 45 required for maintaining the proper warp tension during weaving. The speed of the rollers 19 and 18 is such as to compensate for the natural shrinkage due to picking and to attain the desired tension of the warp. Dials 201 and 202, as 50 shown on Fig. 2, may be provided on casing 12 to indicate the individual speeds. In a diagrammatic manner, Fig. 15 further shows the shafts 10, the swords 6, the cloth winding roller 20, and the warp beam 25.

The cloth winding roller 20 is driven by the cloth carrying roller 18 by means of a belt 63 which in order to provide for the increasing diameter of the roll 20 operates with a slight slip which can be adjusted by means of tension pulley 167 60 mounted on the adjustable lever 72 which is revolvably and adjustably mounted to frame 1.

While I believe the above described embodiments of my invention to be preferred embodiments, I wish it to be understood that I do not 65 desire to be limited to the exact details of process, design and construction shown and described, for obvious modifications will occur to a person skilled in the art.

What I claim is:

1. In a high capacity machine for weaving having gripping shuttles, the combination of 70 ejecting means adapted to eject said shuttles in a direction across the shed, receiving means adapted to receive said shuttles, movable trans- 75

port means for carrying and returning said shuttles from said receiving means to said ejecting means, and operating means connected with and adapted to operate said transport means independently from said ejecting means.

2. In a high capacity machine for weaving having gripping shuttles, the combination of ejecting means adapted to eject said shuttles across the shed, receiving means adapted to receive said shuttles, movable transport means for carrying and returning said shuttles outside of the shed from said receiving means to said ejecting means, and stationary operating means connected with and adapted to operate said transport means independently from said ejecting means.

3. In a high capacity machine for weaving having gripping shuttles, the combination of ejecting means adapted to eject said shuttles in one direction across the shed, receiving means adapted to receive said shuttles, movable transport means located below the shed and adapted to carrying and to return said shuttles from said receiving means to said ejecting means, and stationary operating means connected with and adapted to operate said transport means independently from said ejecting means.

4. In a high capacity machine for weaving, a driving mechanism for driving said machine, a stationary structure comprising two side parts and supporting said driving mechanism, shuttles, thread grippers associated with said shuttles, thread gripper opening means associated with one of said side parts and operatively connected with and operated by said driving mechanism and adapted to engage said shuttles and thread grippers and to thereby open said grippers for releasing the thread, and a thread feeding and thread-gripper closing member associated with the other of said side parts and operatively connected with and operated by said driving mechanism and adapted to engage said thread grippers and to thereby close said grippers for holding the thread.

5. In a high capacity machine for weaving, a stationary structure supporting a driving mechanism, a source of power connected to and operating said driving mechanism, gripping shuttles, picking means supported by said structure and adapted to pick said shuttles across the shed, receiving means supported by said structure and adapted to receive said shuttles after the pick across the shed, said picking means comprising a reciprocable member, engaging means movably connected with and oscillatable relatively to said member for engaging and picking said shuttles, and means for imparting a reciprocating movement to said member, said last mentioned means comprising a source of power which is independent from said first mentioned source of power.

6. In a high capacity machine for weaving, a stationary structure supporting a driving mechanism, a source of power connected to and operating said driving mechanism, gripping shuttles, picking means supported by said structure and adapted to pick said shuttles across the shed, receiving means supported by said structure and adapted to receive said shuttles after the pick across the shed, said picking means comprising a reciprocable member, engaging means movably connected with and oscillatable relatively to said member for engaging and picking said shuttles, means for imparting a reciprocating motion to said member, said last mentioned

means comprising a source of power which is independent from said first mentioned source of power, and control means for periodically engaging said engaging means, and connecting means operatively connecting said control means with said first mentioned driving mechanism for operating said control means.

7. In a high capacity machine for weaving, a shuttle, a cavity within said shuttle, a thread gripper slidably accommodated within said cavity and adapted to be either completely hidden within said cavity or to partly protrude from said cavity and said shuttle, reciprocatingly operated thread feeding means, a thread clamp associated with said thread feeding means, said feeding means being adapted to engage said thread gripper protruding from said cavity and to push said thread gripper completely into said cavity upon a relative movement of said shuttle and said feeding means with respect to one another.

8. In a high capacity machine for weaving, an operating mechanism, a shuttle, a cavity within said shuttle extending substantially along the longitudinal axis of said shuttle, a thread gripper, resiliently spreading jaws associated with said gripper, said gripper being slidably accommodated within said cavity and adapted to be either hidden within said cavity, whereby the jaws are closed, or to partly protrude from said cavity and said shuttle, whereby said jaws spreadingly open, thread feeding means, a thread clamp consisting substantially of resiliently closing jaw members associated with said feeding means, said feeding means being adapted to engage said thread gripper when protruding from said cavity and to push said gripper into said cavity upon a relative movement of said shuttle and said feeding means with respect to each other and to thereby close the jaws associated with said gripper, said thread clamp with the jaw members closed and holding a weft thread protruding from said feeding means and passing through said spreading jaws of said gripper, said jaws of said gripper closing upon the weft thread held by said jaw members upon such relative movement, and spreading means associated with said feeding means for spreading apart said resiliently closing jaw members, and operating means associated with said operating mechanism and adapted to abuttingly cooperate with said spreading means and to thereby open said jaw members after the jaws associated with said shuttle gripper are closed and have taken over the weft thread from said feeding means.

9. In a high capacity machine for weaving, an operating mechanism, a shuttle, a cavity within said shuttle extending substantially along the longitudinal axis of said shuttle, a thread gripper, resiliently spreading jaws associated with said gripper, said gripper being slidably accommodated within said cavity and adapted to be either hidden within said cavity, whereby the jaws are closed, or to partly protrude from said cavity and said shuttle, whereby the jaws spreadingly open, thread feeding means adapted to engage said thread gripper when protruding from said cavity and to push said gripper into said cavity upon a relative movement of said shuttle and said feeding means with respect to one another and to thereby close the jaws associated with said gripper, and a lever associated with said operating mechanism and movably linked to said feeding means for moving said feeding means to and from said shuttle.

10. In a high capacity machine for weaving, a stationary structure having two side parts, a

75

source of power, gripping shuttles having provisions for gripping the weft thread at one end, a slay connected to and operated by said source of power and moving forwards and backwards 5 between said side parts, picking means connected to one of said side parts and being adapted to pick said shuttles in a direction across the shed and being operatively connected with and controlled by said source of power, and receiving means connected to the other of said side parts and being adapted to receive said shuttles, said receiving means comprising movable members which are also connected to and operated by said source of power.

15 11. In a high capacity machine for weaving, a stationary structure having two side parts, a source of power, gripping shuttles having provisions at one end for gripping the weft thread and a point at the other end, a slay operatively connected to and operated by said source of power and moving forwards and backwards between said side parts, picking means associated with one of said side parts and being adapted to pick said shuttles across the shed and being 20 operatively connected with and controlled by said source of power, receiving means connected to the other of said side parts and being adapted to receive said shuttles, said receiving means comprising movable members which are also connected to and operated by said source of power, and gripping means adjacent to the edges of the fabric and being also connected with said stationary structure and connected with and operated by said source of power and being 25 adapted to hold the weft thread until it is beaten up.

12. In a high capacity machine for weaving, means for driving said machine, a stationary structure comprising two side parts and supporting said driving means, shuttles, thread grippers connected with said shuttles, thread feeding means connected with at least one of said side parts and with said driving means and being operated by said driving means and being adapted 40 to engage said shuttles and thread grippers and to thereby adjust said grippers.

13. In a high capacity machine for weaving means for driving said machine, a stationary structure comprising two side parts supporting 50 said driving means, shuttles, thread grippers connected with said shuttles, opening means connected with one of said side parts and operatively connected with and operated by said driving means and being adapted to periodically engage said shuttles and thread grippers and to thereby open said grippers for releasing the thread.

14. In a high capacity machine for weaving, a stationary structure, driving means mounted on said structure and being adapted to drive said 60 machine, said means comprising driving shafts and a cam member on one of said shafts, shuttles, thread grippers connected with said shuttles, control means adapted to engage said shuttles and said thread grippers for adjusting said grippers, and a member movably connected to said stationary structure and to said control means and being adapted to engage said cam member, whereby said control means are operated by said driving means synchronously with said machine.

70 15. In a high capacity machine for weaving, driving means connected to and driving said machine, movable thread holders located adjacent to the fabric edge and connected with and operated by said driving means and holding the 75 weft thread after picking, a reed which is sit-

uated separate from said thread holders and which is also connected with and operated by said driving means yet separately from said thread holders, said driving means comprising cam and lever means for moving said thread holders synchronously with and substantially in the same direction as said reed.

16. In a high capacity machine for weaving, driving means connected to and driving said machine, movable thread holders located adjacent to the fabric edge and connected with and operated by said driving means and holding the weft thread after picking, a reed which is situated separate from said thread holders and which is also connected with and operated by 15 said driving means yet separately from said thread holders, said driving means comprising cam and lever means for moving said thread holders synchronously with and substantially in the same direction as said reed, bending-in means 20 situated separate from said reed and being adapted to turn the ends of the weft thread after beating-up into the following shed, said bending-in means also being connected with and operated by said driving means yet separately 25 from said reed, whereby timed cooperation of said thread holders, said bending-in means, and said reed is assured.

17. In a high capacity machine for weaving, a stationary structure, driving means supported 30 by said structure and being connected to and driving said machine, movable thread holders located adjacent to the fabric edge and connected with and operated by said driving means and holding the weft thread after picking, a 35 reed also connected with and operated by said driving means, said driving means comprising cam and lever means for moving said reed synchronously with and in the same direction as said thread holders, bending-in means adapted to 40 turn the ends of the weft thread after beating-up into the following shed, said driving means comprising a driving shaft and cam means connected thereto, lever means movably connected with said stationary structure and said cam 45 means and said bending-in means, whereby said bending-in means are swingably operated by said driving means, and timed cooperation of said bending-in means, said thread holders and said reed is assured.

18. In a high capacity machine for weaving, driving means connected to and driving said machine, a lay, movable thread holders located separate from said lay and adjacent to the fabric edge and being connected with and operated by 55 said driving means and holding the weft thread after picking, cutting means adapted to cut the weft thread, said cutting means also being located separate from said lay and being connected with and operated by said driving means, whereby timed cooperation of said thread holders and said cutting means and independent operation of said thread holders and cutting means from said lay is assured.

19. In a high capacity machine for weaving, a 65 stationary structure, driving means supported by said structure and being connected to and driving said machine, movable thread holders located adjacent to the fabric edge and connected with and operated by said driving means and holding the weft thread after picking, cutting means adapted to cut the weft thread, said driving means comprising cam means, and said cutting means comprising lever means movably connected with said stationary structure and with 70

75
